UNITED STATES PATENT OFFICE.

EDWARD BEACH GALLAHER, OF PHILADELPHIA, PENNSYLVANIA.

DESIGN FOR A CENTER-BEARING FRAME FOR GAS-ENGINES.

SPECIFICATION forming part of Design No. 34,582, dated May 28, 1901.

Application filed April 13, 1901. Serial No. 55,799. Term of patent 7 years.

To all whom it may concern:

Be it known that I, EDWARD BEACH GALLAHER, a citizen of the United States, and a resident of Philadelphia, in the county of Philadelphia and State of Pennsylvania, have invented and produced a new and useful original Design for a Center-Bearing Frame for Gas-Engines, of which the following is a specification, reference being had to the accompanying drawings, forming part thereof.

Figure 1 is a view in side elevation of the center-bearing frame. Fig. 2 is a view in end elevation of the same, and Fig. 3 is a top plan view.

As shown in the drawings, the leading or material feature of my design is the configuration of a bearing-frame of an engine which will present when viewed in side elevation a circular exterior profile and a broken interior profile which will present when viewed in end elevation an irregular profile formed by a rim *a*, outwardly-extended sleeves *b* and *c* at right angles thereto, the sleeve *b* being spaced from the rim *a* by a bridge *d*, having upper and lower webs *e* connecting the sleeve *b* with

the upper and lower portions of the bridge *d*, and the sleeve *c* being spaced from the rim *a* by a bridge *f*, having an upper web *g* and a lower web *h* connecting the top and bottom of the sleeve *c* with the upper and lower portions of the bridge *f* and which presents an irregular profile when viewed in top plan, formed by the rim *a*, the outwardly-extended sleeves *b* and *c* at one side of the rim and a pair of opposite outwardly-projected lugs *i* and *j* near the other side of the rim *a*, and an interior support *k* projecting beyond the plane of the rim *a*.

What I claim is—

The design for a center-bearing frame for engines, substantially as set forth.

In testimony that I claim the foregoing as my invention I have signed my name, in presence of two witnesses, this 8th day of April, 1901.

EDWARD BEACH GALLAHER.
